UNITED STATES PATENT OFFICE

ANNETTE FRIDOLPH, OF NEW YORK, N. Y., ASSIGNOR TO A. B. A. SPECIALTIES COMPANY, INC., OF NEW YORK, N. Y., A CORPORATION OF NEW YORK

SANITARY WAIST GARMENT

Application filed December 24, 1927. Serial No. 242,419.

My invention is a garment to be worn below the waist line of a female, at the front or at the rear of the person, to preclude visibility of the person occasioned by light 5 through thin garments now so commonly worn, and primarily performing the function of excluding moisture from the body reaching the outer garment, such as a dress, whereby wrinkling of said outer garment arising 10 from the presence of moisture and pressure is minimized.

The garment of my invention is attachable to, and detachable, from an article of female 15 wearing apparel, such as a dress or dress slip, whereby the improved garment may be worn without in any way holding it around the waist of the wearer, thus overcoming a recognized defect in prior garments known as "sanitary aprons" or "shadow proof aprons", 20 the latter being more or less uncomfortable to the wearer both because the weight rests on the waist and of a tendency to become displaced by working its way around the waist due to the motion of the body in walking or 25 while the person is at work.

My garment is detachable at will from the dress or the like, to facilitate cleansing of the improved garment, and to enable the latter to be interchanged with facility upon various kinds of female apparel.

Salient features of my invention are, first, the use of fastening means on the sanitary garment and on the ordinary apparel, whereby the sanitary garment is attachable easily, 35 securely and quickly to the ordinary apparel, and, second, the provision of such fastening means at the margins of the sanitary garment for retaining the latter in a spread out or relatively flat condition, with a view to pre- 40 cluding the sanitary garment from collapsing into a bunched or bundled condition, the latter being uncomfortable to the wearer and tending to defeat the primary purposes of concealing from view the limbs of the wearer 45 and of precluding the accession of moisture to the ordinary apparel.

Other functions and advantages of the invention will appear from the following description taken in connection with the drawings, wherein—

Figure 1 is a view illustrating the sanitary garment to be worn inside of the apparel.

Figure 2 is an enlarged view of the sanitary garment of my invention.

Figure 3 is a detail sectional view of a preferred form of fastening means.

Referring now to Figures 2 and 3, A is the sanitary garment composed usually of moisture proof material, such as a thin layer of rubber or rubberized fabric or of any other material possessing the properties of resistance to the absorption of moisture and of light weight coupled with the necessary durability in service; in short, any material suitable for the purposes may be employed. The 50 garment is of a size and shape to partially cover the person below the waist line, and it is worn at the front or the rear of the body, usually at the rear. Generally speaking, my sanitary garment resembles in large measure 55 an ordinary apron familiar to women, but whereas such aprons are usually worn on the outside and at the front, it is intended that my sanitary garment shall be worn on the inside of the female apparel, usually but not 60 necessarily, at the rear.

Means are provided for attaching the sanitary garment to the female apparel, such as a dress slip, a petticoat, lingerie, or even to the outer dress itself, but it is to be noted that 65 such attachment of the sanitary garment is to be on the inside of the apparel, to the end that the sanitary garment is itself not ordinarily visible or exposed to view. Furthermore, such attaching means are positioned 70 for spreading out the sanitary garment and for retaining the same in a spread out or flattened condition, with a view to precluding the sanitary garment from bunching or bunching. Accordingly, I provide a strip or 75 length of fabric, B, made in a separate piece from the material of the garment A, and also provide a plurality of straps C for co-operation 80 with the strip B, and also provide other fasteners indicated generally at D, E, and positioned at two or more places at the margin 85 of garment A.

The strip B is provided with a plurality of apertures 90 in the form either of eyelets or button holes. This strip B is to be at- 95

tached in any desired way to the female apparel, indicated at G, on the inside of such article G, and at or near the waist line of said apparel. Such attachment of strip B to apparel G is usually by sewing the strip in place, although other modes of attachment may be employed.

The straps C, two or more in number, are composed of fabric, or other material suitable for the purpose, and said straps are attached to the sanitary garment in any desirable way. The straps are positioned at intervals along the upper marginal portion of the garment, from which the straps extend for desired distances. Each strap is provided at the free end with a stiffened tab, c, composed of thin metal of channeled cross section encased within the fabric material of the strap itself, the latter being infolded within the channel of the stiffening agent, as shown in Figure 3, and said channeled metal tab is compressed to effect the permanent union of the fabric and the metal in a way to encase the metal and to afford a rigid cross member at the outer or free end portion of strap C.

The fasteners D, E, are positioned at the marginal portion of the sanitary garment remote to waist strip B and usually at points corresponding substantially to the lower corners of said garment A. Each fastener D or E is constructed as follows:—

A strap d is attached to garment A to protrude outwardly from it, and this strap d is composed usually of fabric with a stiffened tab d', the same being composed usually of metal of channeled cross section. The metal tab is encased within the strap by folding the latter around the metal, and also by infolding the fabric within the channel of the tab, after which the metal is compressed, as shown in Figure 3, with a view to effecting an inseparable union of fabric and metal, wherein the metal is encased to preclude such metal from coming in contact with the flesh of the wearer. A second strap, e, is provided for attachment to the apparel, such as G, and this second strap is furnished with an aperture e', the latter being usually a buttonhole or an eyelet.

To adapt my sanitary garment to a selected article, G, of female apparel, the waist strip B is attached to the article G at or about the waist line, and the straps e, e, of fasteners D, E, are attached at appropriate places to the apparel G, as indicated in Figures 1 and 2. Now to fasten the garment A in place, the tabs c of straps C are thrust through the apertures b of strip B and the tabs d' of straps d are thrust through the apertures e' of straps e. The tabs c, d', thus co-operate with the apertures b and e' of straps B, d, e, to constitute therewith separable fasteners, whereby the garment A is so attached to the apparel G as to preclude in a most effective way the

accidental dislodgment of the garment A from apparel, but at the same time these fasteners may be manipulated easily by the fingers of the operator so as to attach the garment A to apparel G easily and quickly, and similarly, such fasteners may be operated manually with facility for effecting the removal from apparel G of the sanitary garment A for cleaning or other purposes.

In use, the garment A is on the inside of the apparel G to lie between the underwear or the person and the material of apparel G, and thus is within the outer garment, such as a dress. The sanitary garment is not in any way confined around the waist, so that the waist and hips of the wearer are relieved of the weight of said sanitary garment and relieved, also, of the belt or strap usually employed for holding the so-called sanitary apron in position. Furthermore, the sanitary garment is so connected to the apparel that when worn it is retained in a spread-out condition, and with the sanitary garment is associated a number of separable fasteners which act to securely hold the sanitary garment attached to the apparel, whereby the sanitary garment cannot be or become dislodged or displaced, while at the same time said sanitary garment is attached and detached with facility.

My sanitary garment performs important functions in concealing the limbs of the wearer from view when worn in conjunction with thin outer garments, and of excluding moisture from the person or body in reaching the outer garment, whereby the outer garment, when composed of thin materials, does not become wrinkled when a woman sits down. Further, the use of the moisture proof sanitary garment inside of the clothing has a tendency to prevent, or at least to minimize, crushing and wrinkling of velvet dresses, or dresses composed in whole or in part of pile fabrics.

Having thus fully described the invention, what I claim as new and desire to secure by Letters Patent is:—

1. A sanitary and shadow proof garment comprising an apron composed of moisture resistant material, a band separate from said apron, said band being attachable to an outer garment upon the interior thereof and positioned in a spaced relation to the upper margin of said apron, said band having a plurality of apertures, a plurality of straps fixed to the apron and extending upwardly therefrom, each strap having a stiffened tab insertible into an aperture of said band, a plurality of corner straps fixed to the apron substantially at the lower corner portions thereof and extending outwardly, each of said straps having a stiffened tab, and straps attachable to an outer garment and provided with apertures adapted for the reception of the tabs on said corner straps, said band and the specified series of straps cooperating with said

apron for retaining the same in a spread condition upon the interior of an outer garment.

2. A sanitary and shadow-proof apron provided with a plurality of spaced straps, each having a stiffened tab, a plurality of apertured straps adapted to be attached to a garment, said stiffened tabs being insertible into said apertures in the apertured straps to retain the apron in a spread condition on the garment.

10 3. A sanitary and shadow-proof apron provided with a plurality of straps at its top and bottom portions, each strap having a stiffened tab, a plurality of apertured straps adapted to be attached to a garment adjacent said first mentioned straps, said stiffened tabs being insertible into said apertures in the apertured straps to retain the apron in a spread condition on the garment.

20 4. A sanitary and shadow-proof apron provided with a plurality of spaced peripheral straps, each having a stiffened tab at the end thereof, a plurality of apertured straps adapted to be attached to a garment, said stiffened tabs being insertible into said apertures in the apertured straps to retain the apron in a spread condition on the garment.

25 In testimony whereof I have hereto signed my name this 20th day of December, 1927.

ANNETTE FRIDOLPH.
